FURNACE CONSTRUCTION

Reger D. De Wolf, Rochester, N. Y.

Application April 11, 1935, Serial No. 15,841

5 Claims. (Cl. 72—101)

The present invention relates to wall and arch structures for enclosing a heat chamber such as the combustion chamber of a furnace for use with boilers or for other purposes.

- 5 An object of the invention is to provide an improved structure of this class, embodying an efficient, durable and simplified design and one affording economies in the manufacture and upkeep of the same.
- 10 A further object of the invention is the provision of such a structure designed in a manner to facilitate removal and replacement of burned out or damaged parts without weakening the structure or disturbing any adjacent portions thereof and with a minimum loss of time and expenditure for repairs.
- 15 A further object of the invention is to simplify and improve the units or elements of construction of the furnace walls to facilitate assembling of the same and to insure cooperation between the elements to firmly unite and bind them together, whereby to afford a strong and dependable structure which will withstand the strains and stresses to which it may be subjected.
- 20 A further object of the invention is to provide a structure in which all of the elements will be so united and bound together as to insure sufficient strength at all points to take care of the various stresses imposed on the structure and at 25 the same time provide sufficient flexibility to permit the different portions of the structure to give sufficiently to relieve the strains set up by changing temperature conditions whereby to prevent damaging the structure, as by "spalling" or 30 breakage of the refractory elements caused by unrelieved mechanical stresses resulting from too great rigidity of the structure.

35 A further object of the invention is to provide a heat retaining or furnace wall structure of brick-like elements, in combination with a supporting framework and to improve and simplify such a construction in a manner to permit of a reduction in the number of anchoring members or connections between the wall and the framework.

40 A further object of the invention is to provide in combination with a heat retaining or furnace wall of the class described, improved means for insulating and increasing the effectiveness of the construction to insure more economical operation of the furnace.

45 To these and other ends the invention resides in certain improvements and combinations of parts, all as will be hereinafter more fully de-

scribed, the novel features being pointed out in the claims at the end of the specification.

In the drawings:

Fig. 1 is a side elevation of a portion of a furnace wall constructed in accordance with the invention, with the covering partly removed;

Fig. 2 is a sectional elevation on line 2—2 of Fig. 1;

Fig. 3 is a horizontal section on line 3—3 of Fig. 1;

Fig. 4 is a perspective view of a part of the wall shown in Fig. 1, illustrating certain details;

Fig. 5 is a perspective view of one of the hanger blocks of the wall;

Fig. 6 is a perspective view of the wall construction shown in Fig. 1 with the outer covering and insulation removed;

Fig. 7 is a perspective view of one of the recessed bricks adapted to overlie the hanger blocks;

Fig. 8 is a perspective view of the brick shown in Fig. 7, in reversed position;

Fig. 9 is a perspective view of a brick corresponding to those shown in Fig. 6 between the rows containing the anchor blocks;

Fig. 10 is a horizontal section similar to Fig. 3, showing the use of insulating material between the furnace wall and the covering therefor;

Fig. 11 is a horizontal section similar to Fig. 10 showing a modified arrangement of insulation;

Fig. 12 is a horizontal section through a furnace wall having a modified form of skeleton or framework;

Fig. 13 is a sectional elevation taken substantially on line 13—13 of Fig. 12, and

Fig. 14 is a perspective view of a portion of the anchor block supporting means shown in Fig. 13.

The same reference numerals throughout the several views indicate the same parts.

In the embodiment of the invention illustrated in the drawings, there is shown a portion of one of the side walls of a furnace or other heat enclosure which is designated generally by the reference character 10.

There is also provided a skeleton or framework to which the walls of the furnace are tied and with which portions thereof are connected at intervals. The framework in the arrangement shown in Figs. 1 to 4, inclusive, and in Figs. 10 and 11, comprises upright I-beams 11 spaced at intervals along the outside of the walls of the furnace, said beams being provided with suitable braces or connecting members for tying them.

together, which include the horizontal angle bars 12, suitably secured upon the inner flanges of the I-beam as by means of rivets or bolts, not shown. The horizontal flanges 12a of the angle bars constitute ledges for receiving and supporting the anchor blocks 13 of the wall, as shown in Figs. 2 and 3.

The wall structure is formed of refractory or heat resisting elements which are preferably in the form of fire brick or blocks. It will be understood, however, that the form or shape of the elements may be modified as desired and that the elements may be constructed of any suitable heat resisting material.

15 The bricks are constructed in a manner to insure their being positively held in place, one through cooperation with another, as described hereinafter, and they are further secured against displacement by a suitable heat resisting bonding material interposed between the adjacent surfaces thereof.

20 In the present embodiment of the invention there are three forms of brick shown, aside from the hanger blocks 13, these forms being designated generally by the reference numerals 14, 25 15, and 16. The bricks 16 are employed to form the stratified or horizontally disposed layers lying between the layers containing the hanger blocks 13, as best shown in Fig. 6. The brick 16, 30 which have their ends beveled or arranged in convergent relation, are alternately reversed as shown in Figs. 10, 11, and 12, so that the adjacent ends of the brick engage and interlock one with another whereby the brick are tied together 35 and firmly secured one upon another.

35 The bricks 14 overlying the upper layer of brick 16 are each formed with a pocket or recess 14a at one end for the reception of the wings or lugs 13a of the hanger blocks 13 as 40 shown in Fig. 6, whereby the recessed brick are positively held in position by reason of their being in interlocking engagement with the anchor or hanger blocks.

45 The bricks 15 are superimposed directly upon the upper ends of the hanger blocks and are recessed at 15a and provided with pockets 15b for the reception of that portion of the block 13 extending above the bricks 14, including the wings or lugs 13a which take into the pockets 15b 50 to provide for interlocking engagement between the brick and the hanger blocks. It will be seen, therefore, that the hanger blocks afford substantial bearing surfaces for the bricks 15 and that they serve to securely tie the brick to the framework as indicated by the means shown in Fig. 10 55 and described hereinafter.

60 The bricks 16 which are disposed in the layers containing the bricks 15, have their beveled ends in interlocking engagement with the beveled ends 65 of the bricks 15, as shown, for example, in the upper right hand corner of Fig. 6. Thus the layer of bricks containing the hanger blocks and the overlying layer are both securely and directly tied to the framework, through the connection of the hanger blocks with the I-beams 11, as shown, 70 for example, in Fig. 10.

75 Any suitable means may be employed to connect the hanger blocks with the framework such, for example, as the oppositely disposed bracket members or connections 17, the inner ends of which are curved to fit within the vertically disposed grooves 13b of the hanger blocks and the outer ends of which are offset to engage behind the rear flanges of the I-beams, said members 75 being connected one with another and clamped

in position by the bolts 18 as shown in Figs. 10 and 11.

The hanger blocks are directly supported by the angle bars 12, on the horizontal flanges of which the outer portions of the blocks rest as shown in Fig. 2. Thus the weight of the wall is carried by the framework. This is an important and decided advantage since where the furnace structure is of considerable height the weight of the upper portion thereof often bears excessively on and tends to subject the brick of the lower portion to undue strain. Furthermore, if the lower portion of the wall has to be removed and replaced for any reason, it is generally necessary to tear down the whole wall, or the greater part thereof, in which case the upper portion would remain unsupported. With the present construction, however, the framework acts as supporting means for the upper portion, even when the lower portion is entirely removed for repairs. 20

In other words the wall is stratified horizontally so that repairs can be made in each stratum or group of layers independently of the others. With a furnace having walls constructed in the manner shown every layer is either positively 25 held in place or bonded to another layer which is so held in place, whereby a strong and substantial construction is afforded which is adequately braced by the framework and supported thereby to such an extent as to greatly relieve the refractory elements of one stratum from the pressure of another. 30

It will be noted that the hanger blocks tied to the frame each have substantial bearing surfaces for the reception of the surrounding bricks in 35 contact therewith, so that said bricks are securely and positively held against displacement.

The several types of brick shown are formed in such a manner as to render them relatively inexpensive to manufacture and their construction is 40 such as to unite and bind them together in a manner to form a strong and unitary wall structure whereby the number of connections between the wall and the framework can be reduced to a minimum, thus economizing in the cost of the 45 construction of the furnace.

50 It will be understood that the thickness of the furnace walls can be readily increased or decreased by varying the thickness of the refractory elements to the extent desired.

With the present invention the cost of constructing the walls of the furnace is considerably less than it has been heretofore in other furnaces of this general type, and this is particularly true of walls which do not have to be made excessively thick. 55

Instead of employing I-beams in the construction of the framework, as shown in Figs. 1 to 3 inclusive, channels may be substituted for the I-beams as indicated in Figs. 12 to 14 inclusive. 60 In this arrangement the flanges of the channels 19 are extended inwardly, and located between the same and on the web of the channel are a suitable number of angular brackets 20 which may be suitably connected with the web as, for 65 example, by spot welding.

The hanger blocks are supported on the brackets as shown in Fig. 13 and are connected with the channels by means of the straps 21, the inner curved portions of which engage the hanger blocks within the grooves 13b thereof, as shown in Fig. 12. The outer ends of the straps are positioned on the flanges of the channels and are secured thereon by means of the bolts 22 extending through the flanges. The channels may be 75

tied together and braced if desired by suitable means, not shown.

The outer covering of the furnace walls may be

formed of sheets of any suitable material such, 5 for example, as metal or asbestos millboard, or boards formed of other suitable material. Two of the sheets, indicated at 23 in Fig. 3, are positioned upon the outer flanges of the I-beams 11, the joints between the sheets being protected by 10 cover strips 24 secured upon the adjacent edges of the sheets by any suitable means such as the stud bolts 25 which threadedly engage the flanges of the I-beams on opposite sides of the webs thereof.

15 Similar sheets 23a are positioned upon the channels 19, as indicated in Figs. 12 and 13, and may be secured thereon by a plurality of bolts or other suitable means, not shown.

In the embodiment of the invention shown in 20 Figs. 1 to 4, inclusive, the space between the furnace wall and the covering 23 is left open to provide air circulating channels or passages 26 between the I-beams 11, whereby to effectively insure cooling of the walls of the furnace. The air 25 channels may, if desired, be provided with suitable air inlet openings formed in the cover plates adjacent their lower ends, which may be placed under the control of suitable dampers, not shown. If desired the air circulating channels 26 may be 30 made to open into the interior of the combustion chamber for the passage thereto of the heated air arising in and circulating through the channels around the walls of the furnace. However, the air currents admitted to and discharged through 35 the space between the I-beams or channels and the furnace wall proper may be either in an upward or downward direction or in a transverse or crosswise direction.

40 However, instead of providing for the cooling of the walls by the circulation of air around the same, they may be protected by the use of suitable insulation interposed between the cover sheets and the walls, as provided for in each of the modifications shown in Figs. 10, 11, and 12.

45 In the arrangement shown in Fig. 10 the outer face of the furnace wall is provided with an insulating covering 27 formed of any suitable material such, for example, as a plastic or plastic-like material, which may be plastered on or applied in the form of prepared sheets. Furthermore, the space between the insulation 27 and the cover sheets 23 is preferably filled with any suitable loose insulating material as indicated 50 at 28, which is preferably of a fibrous nature or which may be fibrous material pressed together and held by a suitable wire mesh or other means 55 to form a protecting blanket or sheet suitably secured behind the outer cover plates 23.

60 In the arrangement shown in Fig. 11 the insulating material 27a is similar to that indicated at 27 in Fig. 10, except that the sheets are made thicker as shown, when relatively high temperatures are to be maintained in the combustion chamber of the furnace. The loose or compressed 65 blanket type of insulation indicated at 28a is preferably the same as that shown at 28 in Fig. 10.

70 The plastic or plastic-like insulating material shown in Figs. 10 and 11 may be omitted, where relatively low furnace temperatures are to be maintained, in which case the loose or compressed fibrous insulating material shown at 29 in Fig. 12 will be sufficient. However, it will be understood that the nature and quantity of insulating material used may be varied to suit different conditions under which the furnace may

be operated, or to correspond to the different temperatures to be maintained in the combustion chambers.

The arch of the furnace, not shown, may be formed by using the blocks 13 as hanger brick with the brick 14 supported thereby and in interlocking engagement therewith to complete the arch structure.

With the present construction a solid wall of 10 refractory brick is provided for the full depth of the wall, and as previously stated the thickness of the wall may be varied according to varying requirements, by increasing or decreasing the thickness of the brick, within certain limits.

15 By interengaging the beveled or converging ends of the brick and tying them to the spaced hanger blocks a solid unitary wall structure is afforded which obviates the use of a number of specially constructed and expensive parts heretofore employed in walls of this kind. Furthermore the construction is such that the various parts can be more readily assembled and secured than in previous structures of this class so that the labor cost for such work has been considerably reduced, not to mention a reduction in the 20 cost of constructing the several refractory elements disclosed by simplifying the shapes thereof.

25 A further advantage of the present design, as previously stated, lies in the manner of stratifying the structure so that repairs can be made in each 30 stratum independently of the others, whereby the necessity of having to tear down the greater portion of a wall in repairing the furnace, as has been necessary in previously constructed walls of this class, is avoided.

35 As above stated it will be evident that the weight of the layers of face brick lying between the different horizontal rows of hanger blocks will be supported by the hanger blocks in the row next below said layers. For example, in Fig. 40 6 there is shown two horizontal rows of hanger blocks with three layers of face brick therebetween, the weight of which will be supported by the lower row of hanger blocks. This is true for the reason that each of the brick 15 on the hanger 45 blocks of said row supports two of the brick in the layer next above that in which the bricks 15 are disposed. Furthermore the two bricks supported by each of the brick 15 lie beneath and in supporting engagement with three of the brick 50 50 in the second layer above that containing the brick 15. It will be seen, therefore that since the hanger blocks of certain of the rows rest on and are supported by the horizontal angle bars of the frame structure, that the weight of the 55 face brick carried by the hanger blocks of said rows will be transferred to the frame structure, thus greatly relieving the pressure of the brick of one section of the wall from that of the overlying sections.

60 A further and important advantage of the present structure is that none of the parts of the metal supporting structure are embedded in the refractory elements, but on the other hand are free to dissipate the heat to which they are subjected.

I claim:

1. A furnace wall structure, comprising horizontal rows of hanger blocks spaced one above another, horizontal layers of face brick extending between and separating said rows of hanger blocks, each of said hanger blocks having one face brick in one of said layers superimposed thereon and in interlocking engagement therewith said superimposed brick supporting one or 70 75

- more bricks in the layers thereabove, each of said rows having face brick therein at opposite sides of and in interlocking engagement with the hanger blocks, said last mentioned brick engaging the brick of the layers next above and below the same, and a frame structure having parts connected with and supporting said hanger blocks.
2. A furnace wall structure comprising horizontal rows of hanger blocks spaced one above another, superimposed layers of face brick, certain of which layers extend horizontally between said rows and others between the blocks in said rows, the brick in said rows adjacent the opposite sides of the hanger blocks being in interlocking engagement with the blocks, said blocks each having its lower end resting on one brick of one of said layers and each having one brick of another layer superimposed thereon, said superimposed brick supporting one or more bricks in the layers thereabove, said blocks having laterally projecting extensions thereon, and a frame structure having supporting parts for the blocks with which said extensions are connected.
3. A furnace wall structure, comprising horizontal rows of hanger blocks spaced one above another, superimposed layers of face brick certain of which extend horizontally between said rows and others between the blocks in said rows, the bricks in said rows having their adjacent ends formed for cooperation one with another to hold them against lateral displacement each of said hanger blocks having one face brick in one of said layers superimposed thereon said last mentioned face bricks being recessed to receive the blocks on which they are disposed and being in interlocking engagement with said blocks, and a frame structure having parts connected with and supporting said hanger blocks.
4. A furnace wall structure, comprising horizontal rows of hanger blocks spaced one above another, superimposed layers of face brick certain of which extend horizontally between said rows and others being disposed in said rows between the blocks thereof, the blocks of said rows having their lower ends resting on certain of the bricks of the layers next below said rows, a plurality of said blocks each having one face brick in one layer superimposed thereon and recessed to receive said block, said superimposed brick supporting one or more bricks in the layers thereabove, the bricks in certain of said layers having their ends in convergent relation, said ends cooperating one with another to hold said bricks against lateral displacement, said hanger blocks having laterally projecting extensions thereon, and a frame structure having parts connected with said extensions and supporting said blocks.
5. A furnace wall structure, comprising spaced upright supporting members, a plurality of anchor blocks supported on each of said members at one side thereof in spaced relation one above another, the blocks on said supporting members being arranged in horizontal rows, a plurality of layers of face brick extending horizontally between and separating the anchor blocks of said rows, certain of the bricks in the layers next adjacent said rows engaging the ends of the blocks therein, additional face brick being disposed in each of said rows between the anchor blocks thereof and in interlocking engagement with said blocks, and means serving to tie said blocks to said upright supporting members.

ROGER D. DE WOLF.
